UNITED STATES PATENT OFFICE.

ARTHUR B. CROSIER AND FRANK B. CROSIER, OF BELOIT, WISCONSIN.

WASHBOILER.

Application filed September 18, 1922. Serial No. 588,958.

To all whom it may concern:

Be it known that we, ARTHUR B. CROSIER and FRANK B. CROSIER, citizens of the United States, residing at Beloit, in the county of Rock and State of Wisconsin, have invented certain new and useful Improvements in Washboilers; and we do declare the following to be a full, clear, and exact description of the invention, such as will enable others skilled in the art to which it appertains to make and use the same.

This invention relates broadly to clothes washing and dyeing apparatuses but has more specific reference to a device for use in connection with a wash boiler which may be conveniently termed an insert.

The principal object of the invention is to provide a device of this class which is in the form of a false bottom with a fluid conduit rising from it, together with a unique means associated with the latter for controlling the passage of steam therethrough to mingle with and gravitate through the clothes.

Speaking more specifically, it is an object of the invention to provide the above named means which is in the form of a valve for permitting an intermittent action of hot water and then steam on the clothes, whereby to remove all dirt particles and spots in the least possible amount of time.

Inasmuch as the boiling of the water in the tub tends to push the clothes against the top of the latter, it is desirable to prevent this, and it is another object of the invention to provide unique means disposed above the aforesaid insert, this means serving to press the clothes downwardly and to maintain them beneath the level of the water so long as a specified amount is kept in the boiler.

Other features and advantages of the invention will become apparent as the description goes on.

In the accompanying drawings forming a part of this specification and in which like numerals are employed to designate like parts throughout the same:

Figure 1 is a central longitudinal vertical sectional view through a conventional type of boiler showing the improved insert arranged therein for use.

Figures 2 and 3 are horizontal sections taken on the lines 2—2 and 3—3 respectively of Fig. 1.

Figure 4 is a detail perspective view of

the unique means employed for holding the clothes in the water.

Before proceeding with the detailed description of the invention we wish to make it known that although we have shown a definitely shaped insert for use in the ordinary round boiler or tub, we wish it to be understood that the invention is equally well adaptable for use in practically all types of boilers and other washing apparatuses embodying similarly designed containers.

Proceeding with the detailed description, it will be seen that the numeral 1 designates generally a false bottom which is of substantially the same diameter of the tub T or boiler in which it is located. The false bottom is substantially conical in shape and has a down-turned flange 2 surrounding its base portion. In order to permit free circulation of water beneath this flange to promote rapid circulation in the tub, a plurality of circumferentially spaced feet 3 are provided and these rest on the bottom of the tub and space the flange above it. Referring to the apex portion of the conical bottom, it will be seen that this is flat as indicated at 4 and is provided with a plurality of circumferentially spaced hot water escape openings 5. This flattened apex portion is formed with a relatively large central opening from which an upwardly tapered conduit 6 rises. This conduit is provided with circumferentially spaced and vertically spaced apertures 7 to permit the steam to be discharged through them in small jets and it is also formed with a suitably designed head 8 which is such as to spread the steam evenly over the top of the clothes.

It is desirable to permit an intermittent action of the hot water and steam upon the clothes so as to thoroughly cleanse them and as before intimated, the hot water escapes through the openings 5 in the flat apex of the conical bottom and circulates through the clothes and the steam which is generated rises through and is discharged through the apertures in the conduit in small jets to act on the clothes. So as to positively control the action of these two fluids, we have provided the unique valve arrangement. Although this valve construction could be otherwise, we simply prefer to employ a discular plate 9 which is of substantially the same diameter as the flattened apex portion 4 and is suspended normally in

spaced relation below it through the medium of hangers 10 which have their lower ends directed inwardly and extended beneath it. By carefully examining this valve 9, it will be seen that the peripheral portion is imperforate so that when the steam raises it sufficiently it will close the openings 5. However, the plate is formed at its center with circumferentially spaced elongated openings 11 and these serve to permit the passage of steam into and upwardly through the conduit 6 when the hot water openings 5 are closed.

In use, the false bottom 1 is placed in the boiler or tub T in a manner as shown in Fig. 1 and water is placed in the container in the usual way. Then, the device is placed upon a suitable source of heat such as a gas stove. Assuming that the clothes have been placed within the boiler and that the water has started to boil, it will be seen that the water will be elevated and forced through the small escape openings 5 in the flat apex and will circulate through the clothes. As soon as steam is generated however and it becomes of sufficient power, it will act on the valve plate 9 to force it upwardly and to temporarily close the hot water escape openings 5. At this time the steam will pass through the openings 11 in the valve and upwardly through the conduit and will be sprayed in jets through the apertures in the latter. It will thus be uniformly distributed over the clothes to gravitate down through them in the usual way. When the steam pressure recedes, the valve will drop and will permit the hot water openings to be uncovered, whereby to permit the hot water to again act on the clothes. Hence, an intermittent action of hot water and steam on the clothes will be secured and they will be thoroughly cleansed of all dirt.

It has been before intimated that the boiling of the water in the container tends to bulge the clothes and lift them upwardly to an extent to press against the cover and to force some of the clothes completely out of the water. Inasmuch as it is desirable not to fill the container completely to the top with water, and as it is advisable to maintain them in the water at all times to be more effectively cleansed, we propose to use unique means for accomplishing this end. In the showing, this means comprises a wire ring 14 which is provided at diametrically opposite points with small spring coils 15, the upper ends of which are extended laterally as at 16 and then vertically and bent to form heads 17 which are curved slightly to bear against the inner face of the rim of the cover. The spring action of the coils 15 serves to maintain these heads in tight engagement with the cover and the device is thus held effectively in place. The ring is spaced above the sprayer head of the

aforesaid conduit and it prevents, as before stated, the clothes from being bulged upwardly under the action of the boiling water. Hence, they will be maintained underneath the water level and will be more effectively acted on by the boiling fluid and steam. It is of course understood that in practice a predetermined amount of water will be maintained in the boiler and the level will be substantially above the ring 14. Since the latter is immersed slightly in the water it is obvious that it will in turn maintain the clothes submerged in the water and prevent them from boiling up against the closure of the container and forcing it off.

By carefully considering the description in connection with the drawings, persons familiar with devices of this class will doubtless be able to obtain a clear understanding of the invention. Therefore, a more lengthy and detailed description is deemed unnecessary.

Since probably the best results may be obtained with the construction and arrangement herein shown and described, this is taken as the preferred embodiment of the invention. However, we wish it to be understood that minor changes coming within the scope of the invention as claimed may be resorted to if desired.

We claim:

1. A device of the class described comprising a false bottom having a conduit rising from the center of its top, said bottom having a circumferential row of apertures surrounding the conduit at points adjacent thereto, and a single valve normally supported in spaced relation below said apertures, said valve being adapted to be lifted by the steam to simultaneously close all of the apertures, and being provided with a central opening to permit passage of steam through it and into the conduit when said apertures are closed.

2. A device of the class described comprising a substantially conical false bottom for insertion in a clothes container, said bottom having means for supporting its base above the bottom of the container and having its apex portion flattened and equipped with a circumferential row of spaced apertures through which hot water is permitted to escape, a fluid conduit rising from the flattened apex of said body, and a single valve supported in spaced relation below the flattened apex and adapted to be raised by the steam to close said hot water openings, said valve having a central opening aligned with said conduit.

3. A device of the class described comprising a substantially conical false bottom adapted for disposition in the clothes container, said bottom having means for spacing it above the bottom of the clothes container and having its apex portion flattened

and having circumferentially spaced openings, said flattened apex portion being equipped with a relatively large steam escape opening, a conduit rising from said last named opening and being equipped with aertures through which steam is sprayed, hangers depending from said flattened apex portion, and an apertured plate suspended on said hangers and adapted to be acted on by the steam for closing the circumferentially spaced openings of the flattened apex portion.

4. A device for insertion in a clothes container comprising a substantially conical false bottom having a depending flange at its base and circumferentially arranged feet for resting on the bottom of the clothes container, the apex portion of said bottom being flattened and equipped with spaced openings for escape of hot water and with a relatively large central opening, a conduit rising from said central opening, said conduit having openings through which steam is sprayed into the clothing, suspension brackets depending from said flattened por-

tion, said brackets having their lower ends inturned and spaced below said portion, and a plate supported on said inturned ends, said plate forming a valve for said openings and being formed with an aperture which is 30 adapted to permit passage of steam into the conduit when the plate is elevated sufficiently by the steam to close the openings in said flattened apex portion.

5. In a device of the class described, means 35 for maintaining the clothes submerged in a body of water in a container in which said means is arranged, said means comprising a ring of a diameter slightly less than that of the container, a pair of spring coils rising from the ring at diametrically opposite points and terminating in horizontally elongated loops forming heads, the latter being curved to conform to a part of the container with which they are adapted to engage. 40 45

In testimony whereof we have hereunto affixed our signatures.
